UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

CHUCK-RETAINING DEVICE.

1,103,009.

Specification of Letters Patent.

Patented July 7, 1914.

Application filed May 13, 1907. Serial No. 373,319.

To all whom it may concern:

Be it known that I, GEORGE H. GILMAN, a citizen of the United States, residing at Claremont, in the county of Sullivan and State of New Hampshire, have invented an Improvement in Chuck-Retaining Devices, of which the following description, in connection with the accompanying drawings, is a specification, like letters on the drawings representing like parts.

My invention relates to chuck retaining devices for the tools of pneumatic hammers, rock drills or other like devices, being more particularly, though not exclusively, concerned with tool retaining devices for pneumatic hammer drills.

My invention aims, generally, to improve devices of this type and comprises novel features of construction, combination and arrangement of parts, which will be best understood and appreciated by reference to the following description, when taken in connection with the accompanying drawings, of a device embodying one form of my invention and selected for purposes of illustration, its scope being more particularly pointed out in the appended claims.

In the drawings: Figure 1, is an elevation, in partial longitudinal section, of a rock drill apparatus embodying one form of my invention selected for illustration herein. Fig. 2, a longitudinal section of the drill end of the cylinder to show the construction and arrangement of my improved chuck retaining device therein. Fig. 3, a transverse section on the line 3—3, Fig. 2; Fig. 3^a, a perspective view of the inner locking ring; Fig. 4, an end elevation of the drill carrying end of the cylinder; Figs. 5 and 6, are respectively longitudinal and transverse sections of the drill end of the cylinder illustrating a modified construction of chuck retaining devices; Figs. 7 and 8, and 9 and 10 are views, similar and corresponding to Figs. 2 and 3, of other modified forms.

Referring to the drawings and the particular embodiment of my invention selected for illustration therein, I have illustrated my invention as applied to an improved pneumatic hammer tool, herein a drill, employed for drilling rock. The device consists of a suitable cylinder 1, Fig. 1, open at both ends, one, the right, to receive the drill 2, and the left or opposite end, to receive a

slidable feeding piston 3, by which the drill 55 is held up against its work. The cylinder is adapted to be turned by hand during the reciprocatory action of the drill by means of a radially or transversely extending handle 4 and is interiorly provided with suitable devices for periodically actuating the drill. To this end and in the present instance, the drill is struck a series of rapidly recurring percussive, blows by a reciprocating striking plug or hammer 5, Fig. 1, the head of which is shown at the left of Figs. 2, 5, 7 and 9, said hammer being slidably mounted within said cylinder and actuated by a suitable motive fluid, heroin air, which is admitted through the pipe 6 and controlled through an operating handle 7, Fig. 1, the latter also acting to control the admission of air to the feeding cylinder and its piston 3.

Referring now to Figs. 2 and 3, the drill 75 receiving end of the cylinder has, as herein, a longitudinally extending cylindrical recess, the outer end of which is slightly enlarged or provided with a portion of greater diameter to receive a bushing, 8, loosely seated therein against a shouldered portion 9 on the inner surface of the cylinder. This bushing is centrally provided with an axial opening, preferably polygonal in cross section or provided with angular faces, to receive the drill and in which the latter, of corresponding cross sectional area, freely reciprocates but preventing it from rotary movement.

To prevent the bushing and hence the 90 drill from rotating within or independently of the cylinder, suitable means are provided, comprising in one form of my invention, Figs. 2 to 3^a, a slot 10 extending transversely across the ends of the bushing and cylinder and adapted to receive radially and inwardly extending projections or lugs, 11, on the inner face of a lock ring 12, said lugs being the counterpart of and closely fitting into said slot and thereby preventing 100 rotary movement of the bushing within the cylinder, but causing it to move therewith when the handle, 4, is turned in operating the drill. This ring is normally clamped or retained in its inner locking position by 105 means of a slit locking sleeve 13, threaded interiorly to engage screw threads formed upon the outer surface of the cylinder, as

at 14, Fig. 2, and provided, at the sides of the slit portion thereof, with ears 15, Figs. 2 and 4, which receive a clamping bolt 16, the latter in turn receiving a nut 17 by which the sleeve is rigidly clamped to the cylinder, which clamps the bushing and lock ring therein and prevents relative longitudinal, rotary or other movement therein. Said sleeve, 13, is centrally provided with a circular aperture slidably and loosely to receive the shank of the drill and the lock ring 12 and said bushing are provided with apertures or recesses alined therewith, which in the present instance, are both polygonal, herein hexagonal, in cross section to receive the similarly formed shank of the drill. By this construction rotary movement of the drill within the bushing and said locking sleeve are prevented while reciprocal movement is freely permitted. Furthermore, upon turning the cylinder by means of the operating handle 4, Fig. 2, the drill is positively rotated in the same direction and simultaneously with the cylinder, the engaging ends of the feeding piston and the drill forming the pivots about which said cylinder may be turned.

Although my invention, in some of its features, may be usefully applied to threaded bushings, the embodiment thereof just described has the advantage of requiring no coöperating threaded surfaces between the cylinder and the bushings, it being a matter of great difficulty to harden the threaded parts without destroying their fit. In the above embodiment the fit required is not necessarily other than approximate, so that the parts may be hardened and still be interchangeable with other like parts. This construction, furthermore, as in the modifications presently described, is distinctly advantageous over chuck retaining devices or bushings which are retained within the cylinder through the provision of coöperating threaded surfaces just referred to, not only because of the difficulty in hardening them and to produce threads of uniform dimensions, but also because of the expansion produced during the operation of the machine and which practically prevents the removal of the bushings without driving.

In the modified construction represented in Figs. 5 and 6, the locking ring 12 is omitted and in place thereof the outer face 55 of the bushing and the inner face of the large portion of the cylinder are respectively provided with opposed longitudinal recesses, 18 and 19, herein semicircular grooves, to receive a key 20, which prevents movement 60 of one relative to the other. For retaining the key in its bushing in inner position and to lock the bushing against rotary action, therein, the cylinder is provided with a clamping sleeve or cap 21 similar in all 65 respects to that shown in Fig. 2, which

also prevents longitudinal movement of the bushing.

In the modification shown in Figs. 7 and 8, the bushing is similar to that described, the threaded end of the cylinder however, 70 being slit longitudinally to form three similar segments 22, Fig. 8, and exteriorly threaded for a clamping or locking sleeve 21, which is also similar in all respects to that already described. This sleeve may be turned on the cylinder to force the outer split ends of the latter inward or toward one another, the clamping nut 17 and bolt 16 then being adjusted to rigidly clamp the cylinder against the bushing to prevent relative or independent movement thereof. 80

Referring now to Figs. 9 and 10 and to the modification shown therein, the end of the cylinder 1, in the present instance, is slit radially toward its upper side, as best 85 shown in Fig. 10, and is provided, at the sides of the slit, with ears 23 suitably apertured to receive a clamping bolt 24 provided with a nut 25 by which the split portions of the cylinder may be forced together to 90 clamp them rigidly against the bushing to prevent its rotation or relative movement.

In the construction shown in Figs. 7 to 10, wherein the adjacent ends of the cylinder are slotted or cut part way down toward the center, both longitudinal and rotary movement of the bushing is obviously prevented by the pressure produced when the clamping bolt is tightened.

In all forms herein shown, I have provided simple and effective means by which the bushing in which the tool is slidably mounted may be easily removed and which also affords easy access to the striking plug or hammer. Referring to the different 105 views, it will be apparent that all that is necessary to secure the removal of the bushing is to remove the locking sleeve 13 which permits removal of the bushing, the locking ring, or the key 20, as the case may be. 110

So far as I am aware, this is the first instance in the art in which any means have been provided which permit the ready removal of the drill and afford access to the striking plug, all machines of this type with which I am familiar necessitating the dismantling of the machine to a greater or less extent and necessitating driving out the bushing by a drift or similar tool. 115

While I have described my invention with 120 relation to a tool for drilling rock obviously my invention is not limited thereto, nor to the specific construction and arrangement of parts herein selected for purposes of illustration only, the same being capable of 125 modification within wide limits without departing from the spirit and scope thereof.

I claim—

1. An apparatus of the type described provided with a cylinder having an axial re- 130

- cess presenting an enlarged portion of greater diameter at one end thereof and an interior shoulder, an axially apertured bushing loosely received in said enlarged portion and abutting said shoulder, said bushing and an adjacent portion of said cylinder together presenting a recess, a part thereof being in each, a locking member arranged in said recess, and a sleeve for retaining the locking member, said sleeve being provided with means to clamp the same on the end of the cylinder, said sleeve also having an axial aperture to permit free longitudinal reciprocatory movement of a tool therein.
2. A device of the class described having a tool receiving end provided with a longitudinally extending recess forming an interior shoulder, a bushing having angular faces on the interior thereof, mounted in said recess and seated against said shoulder, the tool receiving end and said bushing having opposed recesses, locking means arranged in said recesses for preventing rotary movement of said bushing relative to said end, a tool having angular faces formed to fit the interior of said bushing and an apertured cap clamped to the end of said device to prevent longitudinal movement of said bushing and said locking means relative to said end and to permit free sliding movement of said tool therein.
3. An apparatus of the type described provided with a cylinder having an exteriorly threaded end, a tool receiving bushing permitting longitudinal movement of the said tool therein and having means to prevent rotation of the tool therein, an interiorly threaded sleeve positioned upon the threaded end of said cylinder for preventing outward endwise movement of the bushing, and holding means coöperating with the cylinder, the sleeve and the bushing and engaging the bore of the cylinder and the outer walls of the bushing for rigidly holding the latter within said cylinder to prevent rotary movement of said bushing therein.
4. An apparatus of the type described, comprising in combination, a cylinder, a tool, a piston hammer adapted to strike repeatedly the end of said tool, a bushing mounted in the end of said cylinder adapted to be inserted by a longitudinal sliding movement thereof, said bushing having a non-circular opening in which said tool is non-rotatable but slidably mounted, and means including a part clamped on the end of said cylinder for preventing both longitudinal and rotary movement of the bushing therein.
5. An apparatus of the type described, provided with a cylinder having within one end thereof a bushing for receiving a reciprocatory tool therein, said tool being non-rotatably held by the bushing, and means to lock said bushing against rotative and lengthwise movement including an interiorly threaded split cap for holding said bushing within said cylinder, and clamping means to clamp the cap to said cylinder.
6. An apparatus of the class described, comprising, in combination, a cylinder, a bushing located in said cylinder, a member encircling the end of said cylinder, and a member interposed between and interengaging with the outer end of said bushing and said encircling member and held in position by said encircling member.
7. An apparatus of the type described, comprising, in combination, a cylinder provided at one end with a bushing-receiving cylindrical recess terminating at its inner end in a shoulder, a bushing located within and slidably fitting said recess, and clamping means to clamp said bushing in said cylinder.
8. An apparatus of the type described, comprising, in combination, a cylinder provided at one end with a bushing-receiving cylindrical recess terminating at its inner end in a shoulder, a bushing located within and slidably fitting said recess, and means for positively locking said bushing against rotation, and holding the same against lengthwise movement including an internally threaded sleeve encircling and threaded onto the end of said cylinder, and clamping means to clamp said sleeve to said cylinder.
9. An apparatus of the type described, comprising, in combination, a cylinder provided at one end with a bushing-receiving cylindrical recess terminating at its inner end in a shoulder, a bushing located within and slidably fitting said recess, and means for locking said bushing against rotative and lengthwise movement including means interengaging with said bushing, an internally threaded split sleeve encircling and threaded onto the end of said cylinder, and means to contract said sleeve to clamp the same to the cylinder.
- In testimony whereof, I have signed my name to this specification, in the presence of two subscribing witnesses.
